UNITED STATES PATENT OFFICE

HENRY J. FREEON, OF SANTA MARIA, CALIFORNIA.

EXPANDING DRILL.

1,260,533.

Specification of Letters Patent. Patented Mar. 26, 1918.

Application filed July 11, 1917. Serial No. 179,867.

To all whom it may concern:

Be it known that I, HENRY J. FREEON, a citizen of the United States, residing at Santa Maria, in the county of Santa Barbara and State of California, have invented a new and useful Expanding Drill, of which the following is a specification.

This invention relates to means for drilling oil or Artesian well holes and particularly to a device, adapted to be passed through the well-casing, which will drill a hole of sufficient diameter that the casing may be readily lowered.

The object of the invention is to provide a device of this class which shall be extremely simple and cheap in construction and positive, durable and efficient in operation.

This invention consists generally in an expanding drill comprising in combination a body, a spring actuated mandrel mounted therein, and a bit pivotally mounted on said mandrel, said body provided with a tilting shoulder and upthrust bearing faces, and said bit provided with a surface to contact with and rock upon said shoulder into contact with the bearing faces of said body.

A preferred embodiment of this invention consists in an expanding drill comprising in combination a body, said body provided with a central bore and having one end of the body wall cut away to form a tilting shoulder, a mandrel having its upper diameter reduced to receive a helical spring, a key extending through the body and the mandrel forming a seat for the spring, said mandrel terminating in ears at its lower end, a bit having a stem terminating in a tongue, which tongue is slidably pivoted to the ears of the mandrel, said bit provided with a stepped surface to contact with and rock upon the tilting shoulder of the body.

This invention consists further in the construction and combination of parts herein-after described and particularly pointed out in the claims and will be more readily understood by reference to the accompanying drawings forming a part of this specification, in which,—

Figure 1 is a side elevation with parts broken away illustrating the drill as it appears when passing through the well casing.

Fig. 2 is a front elevation with parts broken away illustrating the drill when in an expanded position ready for drilling.

Fig. 3 is a side elevation corresponding to

Fig. 1 with the drill lowered through the well-casing and the bit expanded into operative position.

Fig. 4 is a side elevation illustrating the expanded drill in operation at the bottom of a well-casing and the bit expanded into operative position.

Fig. 5 is an inverted plan view of the bit.

Fig. 6 is a sectional view along the line x^6 of Fig. 1.

Fig. 7 is a sectional view along the line x^7 of Fig. 1.

As shown by the drawings, 2 represents a body which is formed with a central bore 3. The lower end of the body is cut away to form a tilting shoulder 4, the face 5 of which is inclined downwardly and outwardly toward the periphery. The face 6 of the body is preferably inclined to correspond with the inclination of the face 5, and is in stepped relation thereto. The side face 7 of the shoulder 4 preferably extends at a right angle to the face 5. A mandrel 8 is mounted within the circular bore 3. The upper portion of the mandrel 8 has its diameter reduced to receive the helical spring 9, which spring is held in place under tension by the flanged collar 10 and compressed by the nut 11. The cotter pin 12 locks the nut 11. Through a slot 13 in the body 2 a key 14 extends through an elongated slot 15 of the mandrel 8. The key 14 forms a seat for the spring 9. A pin 16 guards against any possibility of the key 14 slipping out of position. The lower end of the mandrel 8 terminates in two ears 17.

18 represents the bit proper, which is provided with a stem 19 extending into the central bore 3 of the body 2. The stem 19 terminates in a tongue 20 which fits in between the ears 17 of the mandrel 8. Through elongated slots 21 in the ears 17 a pin 22 extends through a hole 23 in the tongue 20 to provide a moving fulcrum point of the bit stem 19 upon the mandrel 8.

An obvious equivalent of the moving fulcrum point would be secured by reversing the slots 21 and the hole 23, constructing an elongated slot in the tongue 20 and suitable holes in the ears 17.

A section of the bit proper 18 is cut away to form the faces 24, 25, which are in stepped relation to form the shoulder 26. The faces 24 and 25 are preferably substantially at right angles to the longitudinal axis of the bit and the side face 27 of the shoulder

26 extends substantially parallel to the longitudinal axis of the bit. The periphery 28 of the bit proper 18 is preferably of the same diameter as the periphery of the body 5. 2. The lower end of the bit 18 is dressed out to form the projection 29 and the cutting edge 30 of the bit is of any construction or design preferred.

The operation is as follows:—While the 10 device is passing through the casing the parts are in the positions shown in Fig. 1. The tension of the spring 9 on the mandrel 8 pulls the bit upward. The outer edge of the face 24 contacts with the outer edge of 15 the surface 5 of the tilting shoulder 4. The opposite lower end face 31 of the bit proper contacts with the interior of the well casing. The side 38 of the stem 19 contacts with the interior wall of the bore 3. In this position 20 the longitudinal axis of the bit is practically in a line with the longitudinal axis of the body and the drill may be lowered readily through the well casing.

As soon as the drill has been lowered below the well casing the parts are in the positions shown in Fig. 3. The tension of the 25 spring 9 on the mandrel 8 pulls upward on the bit. The face 24 of the bit contacts with the inclined surface 5 of the tilting shoulder 30 4 and the bit rocks upon said shoulder. The longitudinal axis of the bit expands at an angle to the longitudinal axis of the body. The face 25 of the shoulder 26 contacts with the inclined face 6 of the body. 35 The side face 27 of the shoulder 26 contacts with the side face 7 of the shoulder 4. The stem 19 pivoted on the pin 22 has slipped along the elongated slots 21 of the ears 17. The side stem 36 of the stem 19 contacts 40 with the interior wall of the bore 3.

When it is desired to withdraw the expanded drill from the well casing, as the 45 drill is raised the periphery of the bit strikes the interior of the well casing and the bit is forced back into alignment with the body 2. The pressure exerted by the well casing causes the bit to rock back on the tilting shoulder and assume the position of Fig. 1.

The construction of this drill is such that 50 it can readily withstand severe strains and jolts from unusual angles. For instance, were the point 34 in the Fig. 3 to strike a projection the strain would be borne by the face 25 of the shoulder 26 contacting with 55 the inclined upthrust bearing face 6. The side face 27 would contact with the side face 7 of the tilting shoulder 4. The side 36 of the stem 19 would contact with the interior wall of the bore 3. The face 24 of the bit 60 would contact with the upthrust bearing 5 of the tilting shoulder 4. In this manner the strain would be evenly distributed and adequately cared for. Likewise, if the corner 35 were to strike an obstacle, the two 65 inclined upthrust bearing faces 5, 6 and the

contact of the stem on the interior wall of the bore would meet and readily care for this strain without any danger of distortion or breaking.

It will be noted that the elongated slots 70 in the ears 17 provide a means for the stem 19 pivoted at the pin 22 to slide. This allows the side 38 of the stem to contact with the interior wall of the bore when in the contracted position of Fig. 1, and by sliding along these elongated slots during the 75 rocking of the bit on the tilting shoulder the opposite side 36 of the stem 19 contacts with the interior wall of the bore when the drill is in the expanded position of Fig. 3. 80

The construction of the tilting shoulder 4 and the shoulder 26 of the bit provides an expanding drill which is practically solid in formation when in the expanded position.

I claim:

1. An expansion drill comprising a body, a spring actuated mandrel mounted therein, and a bit pivotally mounted on said mandrel, the lower end of said body provided with a tilting shoulder and upthrust bearing faces, and said bit extending below the end of said body and provided with a surface to contact with and rock upon said shoulder into contact with the bearing faces of said body. 90

2. An expansion drill comprising a body, a spring actuated mandrel mounted therein, and a bit pivotally mounted on said mandrel, the lower end of said body provided with a tilting shoulder having an inclined bearing face, and said bit extending below the end of said body and provided with a surface to contact with and rock upon said inclined bearing face. 100

3. An expansion drill comprising a body, a spring actuated mandrel mounted therein, and a bit pivotally mounted on said mandrel, the lower end of said body provided with stepped inclined bearing faces, and said bit extending below the end of said body and provided with surfaces to contact with and rock upon said inclined bearing faces. 110

4. An expansion drill comprising a body, a spring actuated mandrel mounted therein, and a bit pivotally mounted on said mandrel, the lower end of said body provided with a tilting shoulder, and said bit extending below the end of said body and provided with a shoulder to contact with said tilting shoulder. 115

5. An expansion drill comprising a body, a spring actuated mandrel mounted therein, and a bit pivotally mounted on said mandrel, the lower end of said body provided with a tilting shoulder and two inclined bearing faces, a side face on said tilting shoulder, and said bit extending below the end of said body and provided with a shoulder and two bearing faces, and a side face on said shoulder. 125

130

6. An expansion drill comprising a body, a spring actuated mandrel mounted therein, and a bit pivotally mounted on said mandrel, the lower end of said body provided with two inclined bearing faces in stepped relation to each other, and said bit extending below the end of said body and provided with two faces in stepped relation to each other to contact with said inclined bearing faces.
7. An expansion drill comprising a body, a mandrel mounted therein, a bit extending below the end of said body and connected to said mandrel, said body provided with a tilting shoulder, spring means to cause such tilting, and a key to form a seat for the spring means.
8. An expanding drill comprising a body, a mandrel mounted therein, and a bit extending below the end of said body, said bit provided with a tongue, said tongue pivoted to said mandrel and adapted to slide transversely within said body.
9. An expansion drill comprising a body, a spring actuated mandrel mounted therein, and a bit slidably pivoted to said mandrel, said body having a tilting shoulder and upthrust bearing faces, and said bit extending below the end of said body and provided with a surface to contact with and rock upon said shoulder.
10. An expansion drill comprising a body, a spring actuated mandrel mounted therein, said mandrel terminating in ears, and a bit, said bit extending below the end of said body and having a tongue pivoted to said ears, said tongue being transversely slidable within said ears.
11. An expansion drill comprising a body, a spring actuated mandrel mounted therein, said mandrel having ears, and a bit, said bit having a tongue slidably pivoted to said ears, said body provided with a tilting shoulder and upthrust bearing faces, and said bit extending below the end of said
- body and provided with a surface to contact with and rock upon said shoulder into contact with the bearing faces of said body.
12. An expansion drill comprising a body, a spring actuated mandrel mounted therein, and a bit slidably pivoted to said mandrel, said bit having a stem adapted to contact on one side of the interior wall of the body when the bit is contracted, and on the opposite side with the interior wall of the body when the bit is expanded.
13. An expansion drill comprising a body, a spring actuated mandrel mounted therein, and a circular bit pivoted to said mandrel, said bit and said body having circumferences of substantially the same diameters.
14. The combination, of a hollow body, a spring-actuated mandrel mounted therein, and a bit provided with a tongue pivoted to said mandrel and adapted to slide transversely within said body, forming an expanding drill having substantially a solid periphery when in an expanded position.
15. A combination, of a circular body, a spring actuated mandrel mounted therein, and a circular bit having the same diameter as said body, said body provided with a tilting shoulder and upthrust bearing faces, and said bit provided with a surface to contact with and rock upon said shoulder into contact with the bearing faces of said body.
16. An expanding drill comprising a body, a spring actuated mandrel mounted therein, a bit pivoted to said mandrel, said bit and said body provided with interengaging surfaces extending completely around the circumference, forming substantially a solid continuous surface when in an expanded position.

Signed at Los Angeles, California, this 3d day of July, 1917.
